CLAIM

The ornamental design for a vending machine, as shown and described.

DESCRIPTION

FIG. 1 is a front and top left perspective view of a vending machine showing our new design;
FIG. 2 is a left side elevational view thereof, the right side being substantially a mirror image thereto;
FIG. 3 is a front elevational view thereof, the rear being substantially flat and unornamented.

FIG. 1

FIG. 2

FIG. 3
